[57] CLAIM

The ornamental design for the “deck connector”, as shown and described.

DESCRIPTION

FIG. 1 is a top perspective view of the deck connector.

FIG. 2 is a bottom perspective view of said deck connector.

FIG. 3 is a front plan view of said deck connector.

FIG. 4 is a side view of said deck connector.

FIG. 5 is a top view of the deck connector.

FIG. 6 is a bottom view of said deck connector.

FIG. 7 is a front view of said deck connector in operation with deck panelling; and,

FIG. 8 is a top perspective view of said deck connector.

The broken line showing of deck paneling in FIGS. 7 and 8 is for illustrative purposes only and forms no part of the claimed design.
